UNITED STATES PATENT OFFICE

154,276

DESIGN FOR A SWING OR SIMILAR ARTICLE

Stanley E. Jones, Cleveland, Ohio

Application August 12, 1947, Serial No. 140,828

Term of patent 7 years

(Cl. D15—11)

To all whom it may concern:

Be it known that I, Stanley E. Jones, a citizen of the United States, residing at Cleveland, Ohio, in the county of Cuyahoga and State of Ohio, have invented a new, original, and ornamental Design for Swings or Similar Articles, of which the following is a specification, reference being had to the accompanying drawings, forming part thereof.

Fig. 1 is a side elevation of a swing embodying my new design.

Fig. 2 is a front elevation of the swing illustrated in Fig. 1.

Fig. 3 is a vertical transverse sectional view of the swing shown in Fig. 1.

I claim:

The ornamental design for a swing or similar article, substantially as shown.

STANLEY E. JONES.
